United States Patent

Des. 238,106

Patented Dec. 16, 1975

238,106

RESUSCITATION BOARD

Dennis Arblaster, 34081 La Serena,
Dana Point, Calif. 92629

Filed Mar. 15, 1974, Ser. No. 451,461

Term of patent 14 years

Int. Cl. D21—02; D24—02

U.S. Cl. D83—1 G

FIG. 1.

FIG. 2.

FIG. 3.

FIG. 6.

FIG. 4.

FIG. 5.

FIG. 1 is a top plan view of a resuscitation board embodying my new design;

FIG. 2 is a side elevational view of FIG. 1;

FIG. 3 is a bottom plan view of FIG. 1;

FIG. 4 is a transverse end view from the left hand side of FIG. 1; and

FIG. 5 is a transverse end view from the right hand side of FIG. 1.

FIG. 6 is a cross-sectional view taken along line 6—6 on FIG. 3.

I claim:

The ornamental design for a resuscitation board, as shown.
